Specification for Design.

Patented July 23, 1912.

Application filed May 14, 1912. Serial No. 697,839. Term of patent 3½ years.

To all whom it may concern:

Be it known that I, WILLIAM D. HENRY, a citizen of the United States, a resident of the village of Manhasset, in the county of Nassau and State of New York, (whose post-office address is No. 1170 Broadway, Manhattan, New York city, New York,) have invented a new, original, and ornamental Design for Textile Fabrics, of which the following is a specification, reference being had to the accompanying drawing, forming part thereof.

The drawing illustrates a portion of the fabric, showing my new design.

I claim:

The ornamental design for a textile fabric, as shown.

WILLIAM D. HENRY.
